UNITED STATES PATENT OFFICE.

CLAUDE MOORE, OF CEDAR RAPIDS, IOWA, ASSIGNOR TO F. L. VERNON, OF NEWTON, IOWA.

PNEUMATIC CAP.

1,426,402.

Specification of Letters Patent. Patented Aug. 22, 1922.

Application filed October 10, 1919, Serial No. 329,746. Renewed November 3, 1921. Serial No. 512,570.

To all whom it may concern:

Be it known that I, CLAUDE MOORE, a citizen of the United States of America, and a resident of Cedar Rapids, Linn County, 5 Iowa, have invented certain new and useful Improvements in Pneumatic Caps, of which the following is a specification.

My invention relates to improvements in pneumatic caps, and the object of my improvement is to supply a double walled inflatable elastic cap for the use of persons swimming, or boating, which will be waterproof, comfortable, and insure the safety of the user while in the water. 10 This object I have accomplished by the means which are hereinafter described and claimed, and which are illustrated in the accompanying drawings, in which Fig. 1 is a side elevation of the pneumatic cap as in 15 place on the wearer, and Fig. 2 is a medial vertical longitudinal section of the same, both said Figs. 1 and 2 depicting the cap in 20 its inflated condition.

Similar numerals of reference denote corresponding parts throughout the several views.

The pneumatic cap shown is made from elastic waterproof material of any suitable kind, such as soft rubber. It may also be of 30 any desired shape or dimensions, as slight variations therein will nevertheless come within the principle of my invention.

The cap comprises an inner or skull-cap 1, preferably shaped to easily conform to the 35 shape of and surround the skull of the wearer elastically when fitted thereon. The numeral 2 denotes an outer enclosure spaced from the cap 1 but united therewith at their edges, and the parts 1 and 2 may be integral 40 or may be separate parts suitably united at their abutting edges, both parts being elastic, waterproof and imperforate, except that the outer enclosure 2 may be provided with an air valve or closable opening or port 4 to 45 permit of proper inflation.

The cap is also preferably supplied with

an elastic marginal strip 3 united thereto all around its edge, which affords the proper tension to the edge coupled with increased strength to hold the edge parts of the cap in 50 tight contact with the person of the wearer to prevent ingress of water.

A pneumatic cap of the character described affords enough additional buoyancy to support the head of the wearer above the 55 water, and hence provides a sure safeguard, for it cannot become displaced upon the person.

This cap may be used by persons in swimming or learning to swim, or whenever it is 60 necessary for one to be in the water, and is desirable for use by persons boating or canoeing especially when the wearer is unable to swim.

Having described my invention, what I 65 claim as new and desire to secure by Letters Patent, is:

1. A pneumatic cap of waterproof elastic material, comprising a skull-cap shaped to firmly hold it on the head of the wearer and 70 an inflatable enclosing cover spaced therefrom.

2. A pneumatic cap, comprising a skull-cap shaped to firmly hold it on the head of the wearer, and an inflatable elastic cover 75 therefor united thereto at their abutting edges.

3. A pneumatic cap, comprising an elastic skull-cap and a spaced elastic surrounding cover therefor, integral therewith, having 80 means for firmly holding them on the head of the wearer, and both imperforate and waterproof.

4. A pneumatic cap, comprising a cup-shaped elastic body with spaced inflatable 85 hollow walls, reinforced around their common edge, to elastically retain it on the head of the wearer and provided with a closable valve.

Signed at Waterloo, Iowa, this 6th day of 90 September, 1919.

CLAUDE MOORE.
